EXPANSIBLE WRISTWATCH BRACELET

John F. Sand, Convent Station, N. J., assignor, by mesne assignments, to The Gemex Corporation, Union, N. J., a corporation of New Jersey

Application August 2, 1954, Serial No. 31,714

Term of patent 14 years

(Cl. D45—4)

Fig. 1 is a top plan view of an expandable wristwatch bracelet embodying my new design;

Fig. 2 is an edge view thereof;

Fig. 3 is a bottom plan view thereof;

Fig. 4 is a top plan view of the bracelet in an expanded condition;

Fig. 5 is an edge view of Fig. 4;

Fig. 6 is a bottom plan view of Fig. 4; and,

Fig. 7 is an enlarged cross sectional view taken on line 7—7 of Fig. 1.

The characteristic feature of the design resides in the continuity of design of the grooves in the alternate inner and outer links of the bracelet when the bracelet is partially expanded.

I claim:

The ornamental design for an expandable wristwatch bracelet, substantially as shown and described.
